UNITED STATES PATENT OFFICE.

EDWARD F. GRAY, OF NEW YORK, N. Y., ASSIGNOR TO GILL BROTHERS COMPANY, OF STEUBENVILLE, OHIO, A CORPORATION OF WEST VIRGINIA.

DESIGN FOR A SHADE.

45,338.

Specification for Design.

Patented Mar. 3, 1914.

Application filed December 9, 1913. Serial No. 805,650. Term of patent 7 years.

To all whom it may concern:

Be it known that I, EDWARD F. GRAY, a citizen of the United States of America, and a resident of 16 East Forty-seventh street, New York city, New York, have invented a certain new, original, and ornamental Design for a Shade, of which the following is a specification.

Referring to the drawings, Figure 1 is a top plan view of the shade. Fig. 2 is an elevation of the shade in upright position.

The external form of the shade is that of a conventionalized acorn or more properly an inverted pear, having meridional convex flutes of varying sizes, the larger flutes 1 having a plurality of small flutes 2 between

them, the lower polar zone or apex portion 3 of the shade being covered with a conventionalized leaf design, the leaves 4 having their surfaces substantially parallel to the surface of the acorn and having their central spines or ribs 5 extended in the direction of the corresponding meridians.

I claim:

The ornamental design for a shade substantially as shown and described.

Signed by me at 16 East 47 St. N. Y. city this 28 day of November, 1913.

EDWARD F. GRAY.
